UNITED STATES PATENT OFFICE.

EDWARD McG. TURNER, OF KNOXVILLE, TENNESSEE.

FRUIT-DRIER.

SPECIFICATION forming part of Letters Patent No. 276,202, dated April 24, 1883.

Application filed January 31, 1883. (No model.)

To all whom it may concern:

Be it known that I, EDWARD MCGAUGHEY TURNER, a citizen of the United States, residing at Knoxville, in the county of Knox and State of Tennessee, have invented a new and useful Fruit-Drier, of which the following is a specification, reference being had to the accompanying drawings.

This invention relates to fruit-driers for baking, drying, and evaporating fruits and vegetables of all kinds; and it consists in certain improvements in the construction of the same, by which a simple, durable, and effective drier is produced, and in which some of the most serious objections in fruit-driers as now ordinarily constructed are removed, as will be hereinafter more fully described, and particularly pointed out in the claims.

In the drawings hereto annexed, Figure 1 is a front view of my improved fruit-drier. Fig. 2 is a vertical sectional view on the line $\alpha\alpha$ in Fig. 1. Fig. 3 is a vertical transverse sectional view on the line $y\gamma$ in Fig. 2. Fig. 4 is a horizontal sectional view on the line $z\zeta$ in Fig. 2. Fig. 5 is a horizontal sectional view on the line $v\nu$ in Fig. 2. Fig. 6 is a detail view of the radiator detached, and Fig. 7 is a detail view of one of the drying-trays.

The same letters refer to the same parts in all the figures.

A in the drawings designates the outer case of my improved fruit-drier, which may be constructed of sheet metal, lumber, or other suitable material, and of any shape desired, either round, rectangular, or elliptical in cross-section or otherwise. In the drawings a casing rectangular in cross-section has been shown. At the corners of this are four vertical flues, B B, extending from the top to some distance below the bottom of the casing, so as to form legs or supports upon which the casing rests, as will be seen in the drawings.

C is a suitably-constructed furnace, located near the bottom and extending from the front to the rear side of the casing. Said furnace has at its front end a feed-door, D, and draft-openings E, and at its rear end it is provided with draft-openings F, which may be covered by a slide, G.

H is a vertical flue, located at the rear end of and outside the casing A, and connected at its lower end with the furnace by an elbow, I, above which a damper, J, is located.

The furnace C is provided with a centrally-located collar, K, projecting upwardly within the casing, and to which the radiator L is connected. Said radiator consists of a suitably-coiled or otherwise constructed pipe, the inner end of which has a vertical pipe, M, by which it is connected with the collar K. Its outer end is connected by a pipe, N, with the draft-flue above the damper J. In the said draft-flue, above the pipe N, is another damper, O. It will be seen that by closing the latter and opening the damper J the products of combustion are compelled to pass through the collar K, radiator L, and into the draft-flue, thus thoroughly heating the interior of the drier. Draft may then be had from both ends of the furnace. By opening both dampers and closing the rear draft, the tendency of the draft will be direct through the elbow I and into the draft-flue. By manipulating the dampers the force of the draft may be regulated in the usual manner.

At the sides of the furnace, in the lower end of the casing, are arranged two slanting deflectors, P P, connecting the front and rear sides of the casing, and extending nearly to the bottom, so that cold air may enter and be thrown by the deflectors P P over against the furnace. From the upper edges of the deflectors P bottom plates, Q Q, extend slantingly upward to the sides of the outer casing. It is between the inner edges of these bottom plates and deflectors that the heat from the furnace enters the drier-casing.

The rear side of the drier-casing is provided at some distance above the furnace with a ledge or flange, R, which serves, in conjunction with side cleats, S S, to support a dished false bottom, T, having a central longitudinal slot, U, over which is placed an inverted box or trough, V, the sides of which are provided with openings W. The heated air, in order to enter the body of the drier-casing, must pass through the slot U and openings W, which serve to diffuse it thoroughly and evenly throughout the drier.

X is the inner case of my improved drier, which is made of sheet metal or other suitable material, conical or pyramidal in shape, its slanting sides being connected to the inner corners of the flues B near the upper ends of the latter, and to the sides of the outer casing at or about the point at which the slanting bot-

tom plates, Q, are connected to the said casing. Between the inner and outer casing are thus formed foul-air spaces or chambers Y, which are connected with the flues B by means of 5 openings Z in the sides of the latter. The moisture-laden air will thus pass from the body of the drier-case over the upper edges of the inner casing or lining into the foul-air spaces Y, from thence through the openings Z and 10 into the flues B, down through the latter, and out through openings A² in their lower ends.

The drier is provided with a top plate, B², from which a flue, C², extends upwardly, as shown. The said flue is provided with a damper, D², and with a cap or cowl, E².

The front side of the drier-casing A is provided, just above the furnace, with a slide-door, F², for admitting cold air into the drier in case the latter should become overheated. The 20 front side of the drier-case is provided with doors G², having double backs H², which are open at the top and bottom, as shown at I². The lower edges of the door-openings are provided with inwardly-projecting ledges or 25 flanges J², having perforations K², enabling the hot air to pass between the front and back sides of the doors, thus preventing the parts of the drier near the doors from becoming cooled by contact with the outer air.

30 L² L² are cleats secured to the inner sides of the flues B, for supporting the drying-trays. The latter, which are denoted by M², may be made of wire-netting, with suitably constructed sheet-metal frames. The said trays are also 35 provided with one or more openings, N², other than those in the netting, and which may be surrounded with collars O². These openings are for the purpose of enabling the heated air to pass through and between the trays and become 40 thoroughly diffused in the drier.

The operation of this invention will be readily understood from the foregoing description, taken in connection with the drawings hereto annexed. The drying-trays are inserted and 45 removed through the doors G². Cold air enters at the bottom of the drier, becomes heated by contact with the furnace and with the radiator, and ascends into the body of the drier-case, where, owing to the peculiar construction herein described, it becomes thoroughly 50 and evenly diffused, thus drying the fruit evenly throughout. The vapors pass over the upper edges of the inner casing into the foul-air spaces, and from thence down and out 55 through the flues B.

I claim as my invention and desire to secure by Letters Patent of the United States—

1. In a fruit-drier, the combination, with the casing, of the vertical flues, arranged within 60 and extending below the bottom of the same, so as to form legs or supports independent of the body of the casing, by which the body of the casing is raised above the floor, as set forth.

65 2. In a fruit-drier, the combination, with the

casing, of the furnace extending from the front to the rear end of the latter, and having draft-openings at its front and rear ends, the draft-flue connected to the rear end of said furnace, a radiator having one end connected 70 to the top of said furnace, coiled within the drier-casing, and having its other end connected to the draft-flue, and dampers located in the latter between the furnace and radiator and above the latter, as set forth. 75

3. The combination of the drier-casing, the furnace, arranged in the lower part of and extending from the front to the rear end of the same, the slanting deflectors, arranged adjoining the sides of the furnace and connected 80 to the front and rear ends of the casing, and the bottom plates, connected to the upper edges of the deflectors and slanting upwardly and outwardly to the sides of the casing, as herein described, for the purpose set forth. 85

4. The combination, with the drier-casing having slanting deflectors and bottom plates, and the furnace and radiator, of the dished longitudinally-slotted false bottom supported upon ledges or cleats within the said casing, 90 as and for the purpose set forth.

5. In a fruit-drier, the combination, with the dished longitudinally-slotted false bottom, arranged substantially as described, of the inverted box or trough placed over the slot in 95 the same, and provided with openings in its sides for the purpose of spreading and diffusing the heated air as it ascends from the furnace, as set forth.

6. In a fruit-drier, the combination of the 100 outer case, the vertical corner flues having openings near their upper and lower ends, the slanting deflectors and bottom plates, and the inner casing having conically or pyramidal slanting sides extending from near the top of 105 the outer case, where they are connected to the inner corners of the flues, to about the point where the slanting bottom plates join the sides of the outer casing, substantially as and for the purpose set forth. 110

7. In a fruit-drier, the casing having door-openings provided at their lower edges with inwardly-projecting perforated ledges, in combination with the doors having false or double backs open at the top and bottom, substantially as and for the purpose set forth. 115

8. In a fruit-drier having the inner slanting-sided casing and provided with the vertical corner flues, as described, the tray-supporting cleats secured to the inner corners of 120 the said vertical flues, substantially as set forth.

In testimony that I claim the foregoing as my own I have hereto affixed my signature in presence of two witnesses.

EDWARD MCGAUGHEY TURNER.
